UNITED STATES PATENT OFFICE.

OLE PAULSON AND JACOB B. NELSON, OF RHAME, NORTH DAKOTA.

OIL-CAN.

1,208,634.

Specification of Letters Patent. Patented Dec. 12, 1916.

Application filed May 7, 1915. Serial No. 26,584.

To all whom it may concern:

Be it known that we, OLE PAULSON and JACOB B. NELSON, citizens of the United States, residing at Rhame, in the county of 5 Bowman and State of North Dakota, have invented new and useful Improvements in Oil-Cans, of which the following is a specification.

The invention relates to oil cans, and 10 more particularly to the class of machine oilers.

The primary object of the invention is the provision of an oiler of this character wherein the parts thereof are readily and 15 easily removed so that in event the said oiler fails to work the same can be conveniently repaired.

Another object of the invention is the provision of an oiler of this character wherein 20 the pump for forcing the oil through the spout can be removed so that the oil will freely flow through said spout, this being done should the pump become inoperative.

A further object of the invention is the provision of an oiler of this character wherein 25 the construction thereof is of novel form to assure the perfect working of the same.

A still further object of the invention is the provision of an oiler of this character 30 which is simple in construction, reliable and efficient in operation, and inexpensive in manufacture.

With these and other objects in view, the invention consists in the construction, combination and arrangement of parts as will 35 be hereinafter fully described, illustrated in the accompanying drawing, and pointed out in the claims hereunto appended.

In the drawings:—Figure 1 is a side elevation of an oiler constructed in accordance 40 with the invention. Fig. 2 is a vertical longitudinal sectional view thereof. Fig. 3 is a sectional view on the line 3—3 of Fig. 2. Fig. 4 is a sectional view on the line 4—4 of Fig. 2.

Similar reference characters indicate corresponding parts throughout the several views in the drawings.

Referring to the drawings in detail, the 50 oiler comprises a body 5 preferably made from metal, and is formed with an inwardly dished bottom 6 and an upwardly arched or semi-spherical shaped top 7, while without the body is a handle 8, the top 7 being 55 formed with a central internally threaded nipple 9 in which is detachably engaged an

externally threaded plug 10 having a plurality of apertures or passages 11, and associated with this plug 10 is a companion plug 12, the same being detachably joined to each other through the medium of an internally threaded collar or coupling sleeve 13 which also detachably connects thereto an outwardly tapered discharge spout 14, and which telescopes over the plug 12, the latter being formed with passages 15 adapted to register with the passages 11 in the plug 10 so that oil from the body 5 will flow therethrough to the spout for lubricating machinery or the like.

Mounted centrally in the inner plug 10 is a feed tube 16 which extends within the body 5 for a portion of the length of the same. Formed in the dished bottom centrally thereof is an internally threaded nipple 17 in which is detachably engaged a screw cap or plug 18, the nipple 17 being formed with an inturned annular flange 19 at its inner end, and insertible through this nipple 17 is a piston barrel 20, one end of 25 which is formed with an out-turned annular flange 21 to engage the flange 19 on the nipple 17, while its opposite end telescopes over the inner end of a hollow boss 22 which projects through the top 7 of the body 5 and 30 carries at its outer end a threaded cap 23 through which works the stem 24 of a piston 25 which is reciprocatingly movable within the barrel 20, and against this piston works a coiled expansion spring 26 which is confined and held suitably seated within the said barrel 20, the spring being designed to automatically move the piston outwardly after being forced inwardly in the barrel, the outer end of the piston stem 24 being 35 fitted with a hand knob 27 for the convenient manipulation thereof.

Spaced from the inner end of the barrel 20 is a conical shaped valve seat 28 for a spherical valve 29 which serves as a check 40 for the backflow of oil when sucked into the barrel 20, the oil being admitted through apertures 30 located between the valve seat 28 and the flanged end 21 of the said barrel. On actuating the piston 25 within the barrel 45 the oil contained therein is under pressure for the feeding of the same to the feed tube 16 which has its inner end extended into the said barrel 20 for communication therewith.

The inner end of the barrel 20 is closed 50 through the medium of a flexible disk 31

which is seated upon the flange 21 and held fast by the plug 18 when engaged in the nipple 17 in the bottom 6 of the body of the oiler. In the use of the pump the oil will be forced under pressure from the body 5 through the spout 14 for lubricating machinery or the like.

The pump structure can be readily removed from the body 5 so that the oiler can 10 be used in the ordinary well-known manner.

Detachably mounted in the top 7 of the body 5 is a cap 32 so that the said body can be conveniently filled with oil when the occasion requires.

15 The end of the feed tube 16 connected with the plug 10 is slightly flared to form a valve seat 32' in which is arranged a valve 33, the same being held in place through the medium of a wire 34 mounted in the flared 20 end of said tube 16, the valve being normally engaged in the seat when the oil can is at rest so as to close the feed tube from admitting atmospheric air to the can.

From the foregoing description, taken in 25 connection with the accompanying drawings, the construction and manner of operation of the device will be clearly understood, and therefore a more extended explanation has been omitted.

30 What is claimed is:—

1. An oiler of the class described comprising a body having a hollow boss formed at its top and also having a dished bottom provided with a central internally threaded 35 nipple, a barrel extended through the nipple in the bottom and engaged with the boss at the top of the body, an annular flange formed on the lower end of the barrel and received in the nipple on the bottom, a closure plug tapped in the nipple in the bottom 40 and engaging the flange on the barrel, a plunger working in the barrel, a spring seated within the barrel and acting upon the plunger, a two-part plug, one part being

detachably mounted in the top of the body 45 centrally thereof, a collar detachably connecting the two parts of the plug, a discharge spout carried by one part of the plug and a valved feed tube leading from the barrel to the two-part plug, said two-part 50 plug being formed with passages for establishing communication between the body and the said spout.

2. An oiler of the class described comprising a body having a hollow boss formed at 55 its top and also having a dished bottom provided with a central internally threaded nipple, a barrel extended through the nipple in the bottom and engaged with the boss at the top of the body, an annular flange 60 formed on the lower end of the barrel and received in the nipple on the bottom, a closure plug tapped in the nipple in the bottom and engaging the flange on the barrel, a plunger working in the barrel, a spring 65 seated within the barrel and acting upon the plunger, a two-part plug, one part being detachably mounted in the top of the body centrally thereof, a collar detachably connecting the two parts of the plug, a discharge spout carried by one part of the plug, a valved feed tube leading from the barrel to the two-part plug, said two-part plug 70 being formed with passages for establishing communication between the body and the 75 said spout, a downwardly tapered valve seat formed in the barrel near the lower end thereof, said barrel being formed with a plurality of apertures below said valve seat, and a valve normally engaged in said seat. 80

In testimony whereof we affix our signatures in presence of two witnesses.

OLE PAULSON.
JACOB B. NELSON.
